UNITED STATES PATENT OFFICE

102,880

DESIGN FOR A DOLL HEAD OR SIMILAR ARTICLE

Marguerite George and Marian Foster, New York, N. Y.

Application August 5, 1936, Serial No. 64,259

Term of patent 14 years

To all whom it may concern:

Be it known that we, Marguerite George and Marian Foster, being citizens of the United States and residents of the city of New York in the State of New York, have invented a new, original, and ornamental Design for a Doll Head or Similar Article, of which the following is a specification, reference being had to the accompanying drawing forming a part thereof, in which:

We claim:

The ornamental design for a doll head or similar article, as shown.

MARIAN FOSTER.
MARGUERITE GEORGE.
